UNITED STATES PATENT OFFICE.

FREDERICK B. McCROSKEY, OF ONTARIO, CALIFORNIA.

ADJUSTABLE REAMER.

No. 892,871.

Specification of Letters Patent.

Patented July 7, 1908.

Application filed July 29, 1907. Serial No. 385,972.

To all whom it may concern:

Be it known that I, FREDERICK B. McCROSKEY, a citizen of the United States of America, and resident of Ontario, in the county of San Bernardino and State of California, have invented certain new and useful Improvements in Adjustable Reamers, of which the following is a specification.

This invention relates to certain new and useful improvements in adjustable reamers, and it has for its objects among others to provide an adjustable reamer which will be capable of performing as satisfactory work as a solid reamer.

15 The only practical adjustable reamer now on the market, so far as I am aware is the blade type but this does not permit of the employment of enough blades or cutting edges by reason of inability to obtain sufficient strength in this style of adjustable reamer. I provide a reamer which overcomes these difficulties by making the entire shell adjustable and thus allowing as many teeth, either straight or spiral, as a 25 solid reamer of the same size. Another and very important feature is the greater strength of such a construction of reamer over one employing narrow blades.

The invention is as applicable to an adjustable tap or an expanding mandrel, as will be evident from the following description.

My present improvement permits of the use of spiral teeth or cutting edges. The 35 adjustable shell which completely surrounds the core is made in sections and is attached to the core in such a manner as to permit of a lateral motion controlled by a threaded collar or by threaded collars, one 40 at each end. Movement of the collar causes the sections of the adjustable shell to change their positions and thus the diameter of the cutting edges is increased or decreased at will, the dove-tail slots 45 being angular with relation to the center line of the core of the reamer.

Other objects and advantages of the invention will hereinafter appear, and the novel features thereof will be particularly 50 pointed out in the appended claim.

This invention, in its preferred form, is clearly illustrated in the accompanying drawings, which, with the numerals of reference marked thereon, form a part of this 55 specification and in which

Figure 1 is a side elevation of a reamer constructed in accordance with my invention. Fig. 2 is a substantially central longitudinal section thereof with parts in elevation. Fig. 3 is an end view looking in the direction of the arrow in Fig. 1.

Like numerals of reference indicate like parts throughout the several views.

Referring to the drawings:—1 designates the core having a threaded shank 2. This 65 core 1 is provided with dove tail ribs 3 as shown clearly in Fig. 3, the cross sectional contour of which may be as found most expedient. This core and the ribs or projections 3 are tapered from the outer end in 70 Fig. 2, and upon these ribs or projections are mounted the outer sections 4 constituting the outer shell of the reamer. These sections are provided with teeth or cutting 75 edges 5 as seen best in Figs. 1 and 3 upon their peripheries so as to form a continuous series of cutting edges or teeth as will be evident from Figs. 1 and 3, giving to the reamer the outward appearance of a solid 80 reamer. The inner faces of these sections of the outer shell are provided with dove tail longitudinal grooves or recesses 6 to conform to the ribs or projections 3 with which they are engaged, as clearly illustrated 85 in Fig. 3.

7 in Figs. 1 and 2 represents a threaded collar engaged with the screw threaded shank and against which the back end of each of the sections 4 of the outer shell rests. By 90 moving this collar the sections are made to change their positions and thus the diameter of the cutting edges is increased or decreased at will, the dove tail grooves or recesses being angular with the center line of the core or 95 the inner sections of the reamer, as will be clearly understood. The incline or taper of the projections and the corresponding recesses or grooves of the sections of the outer shell is clearly seen in Fig. 2.

100 It will thus be seen that I provide a sectional adjustable outer shell which completely surrounds the core and is attached to the same in such a manner as to permit of a lateral motion controlled by a threaded collar. The teeth or cutting edges may be of any desired number, the same as if the reamer were a solid one, and the reamer possesses practically the same strength as if it were made solid. In lieu of the single 105 110

collar herein shown, other means might be employed, for instance a threaded collar at each end such as is employed in the construction shown in my Patent No. 826,109 issued 5 July 17, 1906. In such case I might employ a dove tail to hold the sections, or the threaded collars would serve to hold the sections down, as well as serving for adjustment.

10 As will be clearly seen in Fig. 3, the outer faces of the ribs 3 are curved to conform to the curvature of the outer sections 4, the bottom walls of the grooves 6 being likewise curved. By this means, together with the 15 dovetailed construction hereinbefore described, the outer sections are held down in close contact with the core and accidental disengagement in use is prevented. Furthermore, the contact surface is materially 20 increased. Furthermore, the taper of the core increases from the end of the threaded shank outwardly toward the end where the diameter is the greatest, and the outer sections have a bearing on the adjacent threaded 25 portion of said shank, as seen clearly in Fig. 2, thus giving greater strength at the outer or free end of the reamer.

From the above it will be seen that I have 30 devised a very simple yet durable and efficient construction of adjustable reamer possessing all of the advantages of a solid reamer

in addition to the desirable feature of ease of adjustment, and while the structural embodiment of the invention as herein disclosed is what I at the present time consider preferable, it is evident that the same is subject to changes, variations and modifications without departing from the spirit of the invention or sacrificing any of its advantages. I therefore do not wish to restrict myself to 35 the details of construction herein disclosed, but reserve the right to make such changes, variations and modifications as come properly 40 within the scope of the protection prayed.

What is claimed as new is:—

45 A reamer having a core with dove tail inclined surfaces and of greater diameter at its outer end, a sectional shell provided with peripheral cutting edges and normally completely surrounding said core and having inclined undercut recesses to receive said surfaces, said recesses being angular with relation to the center line of the core, and means on the shank of the core for adjusting said shell.

50 Signed by me at Ontario, California, this 23d day of July, 1907.

60 FREDERICK B. McCROSKEY.
